DESIGN FOR A COOK STOVE

Samuel Klute, South Bend, Ind., assignor to The Malleable Steel Range Manufacturing Co., South Bend, Ind.

Application March 28, 1934, Serial No. 51,208

Term of patent 7 years

To all whom it may concern:

Be it known that I, SAMUEL KLUTE, a citizen of the United States, residing at South Bend, in the county of St. Joseph, State of Indiana, have invented a new, original, and ornamental Design for a Cook Stove, of which the following is a specification, reference being had to the accompanying drawing, forming a part thereof.

The figure of the drawing is a perspective view of the cook stove embodying my new design.

I claim:

The ornamental design for a cook stove as shown.

SAMUEL KLUTE.
